(57) **CLAIM**

The ornamental design for an adjustable shaft cover, as shown and described.

DESCRIPTION

FIG. 1 is a top, left, front perspective view of an adjustable shaft cover showing a first embodiment of the new design, illustrating the article in a first configuration;

FIG. 2 is a top view of the invention illustrated in FIG. 1; FIG. 3 is a rear view of the invention illustrated in FIG. 1; FIG. 4 is a left side view of the invention illustrated in FIG. 1;

FIG. 5 is a right side view of the invention illustrated in FIG. 1;

FIG. 6 is a front view of the invention illustrated in FIG. 1; FIG. 7 is a bottom view of the invention illustrated in FIG. 1;

FIG. 8 is a top, left, front perspective view of the invention illustrated in FIG. 1, illustrating the article in a second configuration;

FIG. 9 is a partially exploded top, left, front perspective view of the invention illustrated in FIG. 1;

FIG. 10 is a top, left, front perspective view of an adjustable shaft cover showing a second embodiment of the new design, illustrating the article in a first configuration;

FIG. 11 is a top view of the invention illustrated in FIG. 10; FIG. 12 is a rear view of the invention illustrated in FIG. 11; FIG. 13 is a left side view of the invention illustrated in FIG. 11;

FIG. 14 is a right side view of the invention illustrated in FIG. 11; FIG. 15 is a front view of the invention illustrated in FIG. 11; FIG. 16 is a bottom view of the invention illustrated in FIG. 11;

FIG. 17 is a top, left, front perspective view of the invention illustrated in FIG. 11, illustrating the article in a second configuration; and,

FIG. 18 is a partially exploded top, left, front perspective view of the invention illustrated in FIG. 11.

The broken lines in the drawings depict portions, or environment, of the adjustable shaft cover that form no part of the claimed design.

1 Claim, 14 Drawing Sheets
